UNITED STATES PATENT OFFICE.

FRANK TRUMAN GOODWIN, OF TORONTO, CANADA, ASSIGNOR TO DAVID JOHN ARCHER, OF TORONTO, CANADA.

BURNER FOR CRUDE OIL.

SPECIFICATION forming part of Letters Patent No. 768,798, dated August 30, 1904.

Application filed October 1, 1903. Serial No. 175,399. (No model.)

To all whom it may concern:

Be it known that I, FRANK TRUMAN GOODWIN, a subject of the King of Great Britain, residing in the city of Toronto, in the county 5 of York, in the Province of Ontario, Canada, have invented certain new and useful Improvements in Burners for Crude Oil, of which the following is a specification.

My invention relates to improvements in burners for crude oil; and the object of my invention is to provide a cheap and efficient burner of the class described and one that can be used in connection with any suitable stove or furnace; and it consists, essentially, of a 15 burner provided at its combustion end with a peculiarly-constructed perforated base and at its upper end with perforations or holes through which air passes thereinto, a suitably-constructed grid secured at or near the combustion end of said burner, and a suitable feed-pipe for said burner, as hereinafter more particularly explained.

Figure 1 is a vertical central section through my burner, showing construction of same and 25 a suitable stove to illustrate how the burner operates. Fig. 2 is a cross-section on the line 1 1, Fig. 1.

In the drawings like characters of reference indicate corresponding parts in each figure. 30 A is the burner, to the combustion end of which is secured a hollow base B, provided with suitable perforations b. Suitably secured to the base B is a drip-pan C, the center portion of which is provided with a cup D, in 35 which is collected the particles of oil that may not be comminuted sufficiently by the grid E, which is suitably placed in the combustion end of said burner A. It will of course be seen from the drawings that the cup D is immediately below the grid E in the combustion end 40 of the burner A.

In Fig. 1 I have shown my burner supported within any suitable stove F. In the construction shown the said burner is provided 45 with a flange a, by means of which the device is held in the stove.

G is any suitable feed-pipe for the crude

oil leading from the reservoir H down into the burner A.

I is any suitable stop-cock for regulating 50 the supply of oil in the burner.

By reason of the openings J in the top of the burner A a downdraft of air is always passing through the burner and base B in the direction indicated by arrow and up out of the 55 stove through the flue O. The oil drops from the end of the feed-pipe G onto the bars e of the grid and is comminuted, thereby enabling the downcurrent of air to mix with same. The oil and air are ignited, and by reason of 60 the said downdraft the flames pass out of the perforations b, as shown by arrow. During the operation of the burner the drip-pan C becomes thoroughly heated, and any oil that 65 may be collected in the cup D is heated and ignited. By reason of the downdraft there will be no possibility of any smell or smoke escaping from the burner.

As shown in the drawings, I preferably bolt the drip-pan C to the base B by any suitable 70 bolt c.

Although I have shown the burner A as being provided with a separate perforated top P, I do not confine myself to this construction, as it is quite evident that the top P may be 75 formed integral with said burner. The oil of course is fed by gravity from the feed-pipe G. It will of course be understood that the openings or holes b may be of any suitable size and shape.

In my preferred form of construction the perforations or openings b are made in the base B above its outwardly-flared flange 3, and the drip-pan C is provided with a flange 4, bolted to said flange 3.

I hereby claim that I may make such alterations in the construction of my burner as will not be a departure from the spirit of my invention.

What I claim as my invention is—

1. A device of the class described comprising a burner A provided with perforations at its upper end through which air passes thereinto; a grid secured at the combustion end of

said burner; a base also secured over the combustion end of said burner provided with suitable openings through which the flames pass therefrom; a drip-pan suitably secured to said 5 base and provided with a cup directly beneath the combustion end of the burner A in which oil may collect, and a suitable feed-pipe extending into said burner.

2. A device of the class described comprising 10 a burner A provided with perforations at its upper end through which air passes thereto, and a flange by means of which the burner is held in place; a grid secured within said burner at its combustion end; a base also secured 15 over the combustion end of said burner provided with suitable openings through which the flames pass therefrom; a drip-pan suitably secured to said base and provided with a cup directly beneath the combustion end of 20 the burner A in which oil may collect, and a suitable feed-pipe extending into said burner.

3. A base for crude-oil burners provided 25 with an upper central opening, and a series of openings or holes formed in its lower portion above its outwardly-flared flange 3, through which the flames pass therefrom; a drip-pan secured to said base, provided with a cup or depression immediately below said central upper opening in said base, and being further 30 provided with a flange 4 by means of which it is secured to the flange of said base, and a grid

secured in the upper central opening of said base by means of which the oil is comminuted as it passes into said base.

4. A device of the class described comprising 35 the burner A provided with perforations at its upper end through which air passes thereto; a grid secured at the combustion end of said burner; a base also secured over the combustion end of said burner provided with suitable openings through which the flames pass therefrom, and a drip-pan suitably secured to 40 said base and provided with a cup directly beneath the combustion end of the burner A in which oil may collect, as described.

5. A base for crude-oil burners provided 45 with an upper central opening, and further provided with suitable openings through which the flames pass therefrom; a drip-pan suitably secured to said base and provided with a cup or depression immediately below said central upper opening, and a grid secured in the upper central opening in said base by means of which the oil is comminuted as it passes into 50 said base.

In testimony whereof I have signed my name to this specification in the presence of two subscribing witnesses.

FRANK TRUMAN GOODWIN.
